REFRIGERATION APPARATUS

Martin G. Sateren, West Springfield, Mass., assignor to Westinghouse Electric & Manufacturing Company, East Pittsburgh, Pa., a corporation of Pennsylvania

Application February 21, 1940, Serial No. 320,042

2 Claims. (C.I. 62—102)

My invention relates to refrigeration apparatus and particularly to a high humidity refrigerator for improving the storage of foods which are subject to dehydration.

It is an object of my invention to provide an improved and novel path for the flow of air in a high humidity refrigerator.

It is also an object of my invention to so construct a high humidity refrigerator that the temperature of the air in the food storage compartment is relatively low and the relative humidity therein is high.

It is another object of my invention to construct a high humidity refrigerator so that substantially the same refrigeration unit may be used both for high humidity refrigerators and for conventional refrigerators, in the latter of which the cooling element or evaporator is exposed directly to the air in the main food storage compartment.

These and other objects are effected by my invention as will be apparent from the following description and claims taken in connection with the accompanying drawings, forming a part of this application, in which:

Fig. 1 is a sectional view of a refrigerator embodying my invention; and,

Fig. 2 is a sectional view of a refrigerator taken along the line II—II of Fig. 1.

Referring specifically to the drawings for a detailed description of my invention, numeral 10 designates generally an insulated refrigerator cabinet embodying a high humidity compartment 11, an evaporator compartment 12 and a machinery compartment 13. An evaporator or cooling element 14 is disposed in the evaporator compartment 12 and is connected by suitable conduits to a refrigerating unit generally indicated at 15 disposed in the machinery compartment 13. The refrigerating unit 15 includes a sealed casing 16 enclosing a main motor 17 and a compressor 20. The compressor 20 withdraws refrigerant vapor from the evaporator 14 through conduit 14a and compresses it into a condenser 18 wherein the high-pressure refrigerant is cooled and liquefied, aided by air blown over the condenser by a motor-driven cooling fan 19. Condensed refrigerant is then fed to the evaporator 14 through a capillary tube flow-restricting device 21, after which the refrigerant evaporates and absorbs heat. The cycle is then repeated.

The high humidity compartment 11 is formed by a liner 22 which is spaced from an inner shell 23 of the refrigerator cabinet 10, thus providing a passageway 24 around the top, bottom, sides,

and rear walls of the liner 22. The liner is formed of a material having a low thermal drop therethrough and preferably of good heat conductivity, such as porcelainized steel and is provided with an access opening 25 at its front which is closed by a door 26. The space at the front of the cabinet between the inner shell 23 and the liner 22 is sealed by a breaker strip 27.

The evaporator compartment 12 is formed to substantially isolate the evaporator 14 from direct contact with the air in the high humidity compartment 11 and comprises a shroud 28 spaced from the sides and bottom of the evaporator 14 and fastened to top and rear walls 29 and 31 of the liner 22. An auxiliary access door 32 seals the front of the shroud 28 and affords access to the evaporator where ice is usually frozen in ice trays (not shown) which are disposed in a freezing space 33 formed by imperforate walls 34 of the evaporator. A refrigerated shelf 30 divides the freezing space 33 into an upper portion 33a and a lower portion 33b.

The high humidity chamber 11 is primarily cooled by the conduction of heat through the metallic liner 22 to the air in the passage 24 in the following manner. The rear of the freezing space 33 connects with a fan inlet opening 36 in the rear wall 31 of the inner liner. A fan 37 driven by a motor 38 is disposed in the passageway 24 in registry with the fan inlet opening 36. A second opening 39 in a top wall 29 of the inner liner 22 establishes communication between the passageway 24 and the interior of the evaporator compartment 12. A baffle 41 is disposed completely across the width of the passageway 24 between liner 22 and shell 23 and as shown in Fig. 2 extends across the top of the inner liner 22 and down its sides almost to the bottom thereof. It is also to be noted that the evaporator 14 is spaced from the rear wall 31 of the inner liner 22.

Air is, therefore, drawn into the evaporator chamber 12 through the upper opening 39 and passes simultaneously over the inner and outer surfaces of the imperforate walls 34 of the evaporator 14. The air which passes over the inner surfaces of the imperforate walls 34 passes through the upper freezing chamber 33a in contact with the refrigerated shelf 30 and into the fan inlet 36. The air passing on the outside of the imperforate walls 34 of the evaporator 14 enters the lower chamber 33b either at the front or the rear end thereof and then enters the fan inlet 36. The air in passing over the cold evaporator is cooled and dehumidified, it being pref-

erable that the fan motor 38 and the main motor 17 be energized at the same time.

Cold air from the fan 37 is discharged over the entire exterior surface of the rear wall 31 of the inner liner 22, this part of the passageway 24 constituting a high air pressure zone. The baffle 41 guides the cold air to the bottom of the inner liner 22 and, as shown by the arrows in Figs. 1 and 2, the cold air is conveyed along the bottom, up the sides and over the top of the inner liner 22 to the upper opening 39 therein, thus completing the air circuit. It is to be noted that the cold dry air does not enter the high humidity chamber 11 and that the air pressure in the passageway 24 progressively decreases from the point of discharge at the fan to the upper opening 39 in the inner liner 22. Furthermore, the high humidity compartment 11 is cooled primarily by conduction of heat through the metal walls thereof to the air in the passage 24. The air in the high humidity compartment 11 is, therefore, effectively cooled by an extended heat transfer surface comprising the inner liner 22 and a high humidity is, therefore, maintained in the compartment 11.

The evaporator 14 has refrigerating capacity stored therein when the refrigerating mechanism 15 is not operating and if the fan is inactive at the same time, thermosyphonic circulation of air will occur in the passageway 24 thus cooling the high humidity compartment 11 during inactive periods of the refrigerating mechanism 15.

From the foregoing it will be apparent that I have provided a high humidity cabinet having improved air circulation for cooling and maintaining a relatively high humidity and low temperature in a refrigerator cabinet. Furthermore, it will be apparent that a refrigerating mechanism 15 and evaporator 14 such as used in conventional low humidity refrigerators may be utilized to construct a high humidity refrigerator.

While I have shown my invention in but one form, it will be obvious to those skilled in the art that it is not so limited, but is susceptible of various changes and modifications without departing from the spirit thereof, and I desire, therefore, that only such limitations shall be placed thereupon as are specifically set forth in the appended claims.

What I claim is:

1. In refrigeration apparatus, the combination of a refrigerating unit including a cooling element and means for circulating refrigerant through the cooling element, a refrigerator cabinet including a liner having rear, bottom, side, and top walls formed of a material having a low thermal drop therethrough and enclosing a food storage compartment, said food storage compartment having an open front means for substantially isolating the cooling element from the food storage compartment, a duct system surrounding said liner, air circulating means for forcing air through said duct system and over said cooling element to cool the food storage compartment primarily by conduction of heat through said liner, said duct system being arranged so that as air leaves the cooling element it is conveyed first into contact with the entire back wall of the liner, then forwardly toward said open front of the food storage compartment under the bottom of the liner, and up both sides thereof in contact with the liner to the top of the liner whereupon it reenters the cooling element, said duct system being formed in part by baffles which extend across the exterior of the top of the rear wall of the liner and downwardly along the exterior of the vertical edges of the rear wall of the liner to a point adjacent the bottom wall of the liner.
2. In refrigerating apparatus, the combination of a cabinet having side, rear, top, and bottom walls and an open front, a door for said open front, heat insulating material on said cabinet and on said door, a metal liner in said cabinet adjacent to but spaced from at least one side, rear, top, and bottom wall, said liner having two openings in the upper portion thereof, a partition in the upper portion of said liner said partition forming a compartment communicating with both of said openings, a cooling unit in said compartment, means for circulating air through said compartment, said air entering said compartment through one of said openings and leaving through the other of said openings, and a shroud between the liner and at least one wall of said cabinet to direct air issuing from one of the openings toward said bottom wall.

MARTIN G. SATEREN.
